ILLUMINATED TRAFFIC SIGNALLING AND DIRECTING UNIT

Arthur E. Kaiser, Seattle, Wash.

Application March 27, 1958, Serial No. 50,204

Term of patent 14 years

(Cl. D72—1)

Fig. 1 is a view in front elevation of an illuminated traffic signalling and directing unit, showing my new design;

Fig. 2 is a view in rear elevation; and

Fig. 3 is a view in side elevation.

The dominant features of my design are shown in full lines.

I claim:

The ornamental design for an illuminated traffic signalling and directing unit, substantially as shown and described.
